UNITED STATES PATENT OFFICE.

AMÉDÉE TROUTTET, OF NEW YORK, N. Y., ASSIGNOR TO MARY ANN TROUTTET, OF SAME PLACE.

GLOVE-FASTENER.

SPECIFICATION forming part of Letters Patent No. 292,450, dated January 22, 1884.

Application filed July 23, 1883. (No model.)

To all whom it may concern:

Be it known that I, AMÉDÉE TROUTTET, of the city, county, and State of New York, have invented a new and Improved Glove-Fastener, of which the following is a full, clear, and exact description.

Reference is to be had to the accompanying drawings, forming part of this specification, in which similar letters of reference indicate corresponding parts in all the figures.

Figure 1 is a plan view of the wrist portion of a glove, having my new and improved glove-fastener applied thereto. Fig. 2 is a sectional elevation of the same, taken on the line *xx* of Fig. 1. Fig. 3 is a sectional elevation of the button secured to the free end of the fastening-strap, and Fig. 4 is a perspective view of the sliding buckle or fastener removed from the fastening-strap.

The invention will first be described in connection with the drawings, and then pointed out in the claims.

In the drawings, A represents the fastening-strap. This is formed with a series of holes, *a a*, and is secured by the eyelets *b* to the flap B of the wrist of the glove, and upon the fastening-strap A is placed loosely the sliding buckle or fastener C. The flap D of the wrist of the glove is provided with the eyelets *c c*, and has formed in it the button-hole *d*, and upon its under side it is provided with the shield-piece *e*, preferably of stiff thin leather, that serves to prevent the flap from being folded under in the act of fastening the glove, and also to protect the wrist of the wearer from the eyelets *c c*, button *f*, and hook *g* of the buckle or fastener C. The buckle or fastener C is skeleton or loop shaped, as shown clearly in Fig. 4, and the forward bar, *h*, thereof is formed with a hook, *i*, that is adapted to catch into one or other of the eyelets *b*, or one or other of the holes *a*, made in the strap A, according to the size of the wrist, and the rear bar, *h'*, of the buckle or fastener C is formed upon the under side with said hook *g*, that is adapted to catch into one or other of the eyelets *c*. The buckle or fastener C is placed upon the fastening-strap A by simply passing the strap A through the opening *j* of the buckle, as shown clearly in Fig. 2, and the

buckle is prevented from sliding off from the fastening-strap A by the ornament J, attached to the free end of the strap A, which ornament is larger than the opening *j* of the buckle. The ornament J might be a mere metallic ornament to give a finished appearance to the end of the strap A, and to serve for keeping the buckle upon the strap A; but instead of the ornament J any other suitable means for keeping the buckle upon the strap might be used. 55

But I prefer to use the ornament J, and I prefer to form it with the button portion *f*, above mentioned, which is adapted to be passed through the button-hole *d*, after the glove is fastened, for holding the free end of the strap A down and in proper position close to the wrist, as will be understood from Fig. 2; and I prefer to form the ornament J in two parts—viz., the said button portion *f* and the clamp part *f'*—which parts are adapted to be screwed together by the screw-threaded shank *e'*, formed upon the part *f'*, entering the screw-threaded tap *i'*, formed in the button part *f*, for convenience in attaching the ornament to the strap A. 7c

In use, while the glove is being put upon the hand, it will be understood that all parts of the improved fastener will be detached from the flap D. The glove having been drawn fully upon the hand, the buckle or fastener C will be drawn outward upon the fastening-strap A toward the ornament J, and the hook *g* of the buckle will be caught in one or other of the eyelets *c*. Then, by drawing upon the free end of the strap A, the flaps B D of the wrist of the glove will be drawn together, the 80 buckle C sliding upon the strap until the flaps of the glove are brought snugly around the wrist. The hook *i* will then be caught in one or other of the eyelets *b*, or one or other of the holes *a*, made in the strap A, which will 90 securely fasten the glove. The button *f* of the ornament J will then be passed through the button-hole *d*, for holding the free end of the strap A down to the wrist, as will be understood from Fig. 2. To unfasten the glove, 95 the ornament J is simply to be unbuttoned from the button-hole *d*, and then the hook *i* is to be lifted out of the eyelet *b* or hole *a*, as the case may be, which will permit the strap A to slide through the buckle C, thus enabling the 100

hook *g* to be easily detached from the eyelet *C*, which being done will set the flaps *B* *D* of the glove entirely free.

To the flap *B*, upon the under side, is secured 5 the facing *k*, of some thin stiff leather, which prevents the corner of the flap *B* from being folded under when the glove is being fastened.

Thus constructed, it will be seen that the 10 fastener is very convenient, quick and easy to operate, requiring no glove-hook or other device for fastening the glove, and that the device is cheap, novel, and practical.

Having thus described my invention, I claim 15 as new and desire to secure by Letters Patent—

1. In a glove-fastener, the sliding buckle or fastener *C*, provided with the hooks *i* and *g*, and placed upon the fastening-strap *A*, and arranged to operate substantially as described.
- 20 2. The strap *A*, attached to the flap *B* of the

glove, and having suitable holes or eyelets, in combination with the buckle or fastener *C*, having hook *i* and hook *g*, and the flap *D*, having suitable holes or eyelets for receiving the hook *g*, substantially as described.

25 3. The fastening-strap *A* and sliding buckle *C*, in combination with the button *f*, attached to the free end of the strap *A*, for holding the buckle in place upon the strap, and for fastening the strap down to the wrist, substantially as described.

30 4. The flap *D* of the glove, provided with suitable holes or eyelets, *c*, and button-hole *d*, in combination with the strap *A*, sliding buckle *C*, and button *f*, substantially as and for the 35 purposes set forth.

AMÉDÉE TROUTTET.
